UNITED STATES PATENT OFFICE.

HENRY W. FISHER AND RALPH W. ATKINSON, OF PERTH AMBOY, NEW JERSEY, AS-
SIGNORS TO STANDARD UNDERGROUND CABLE COMPANY, OF PITTSBURGH, PENN-
SYLVANIA, A CORPORATION OF PENNSYLVANIA.

CONSTRUCTION OF CABLES.

Original application filed July 2, 1920, Serial No. 393,574. Divided and this application filed May 17, 1924. Serial No. 714,011.

In Letters Patent of the United States, No. 1,524,124, granted Jan. 27, 1925, we have described and claimed a certain cable structure adapted for use for the transmission of electric power. The cable structure of the patent contains this informing idea: to put under pressure, and ordinarily under heavy pressure, such air as may accidentally be found, or may designedly be present, within 10 the insulation of the cable conductor. Cables of the character with which we have to do, are cables which are required to carry currents under pressure of ten thousand volts and upward, and our invention, which 15 centers in the maintenance under pressure of air within the cable structure, has in view the production of an insulating envelope which shall excel insulating envelopes heretofore employed, both in the matter of dielectric strength, and in the matter of security against leakage.

Our present application is a divisional application, derived from our patent mentioned above, and the invention as we shall herein 25 describe and claim it, is found in a specific employment of the general idea.

Electric cables of the class with which we have to do consists essentially of conductor, insulation, and sheath. There may be a single conductor within a cable, made up of a single strand or of many strands, or there may be a plurality of conductors. Ordinarily there are three. These conductors are enveloped in insulation; this insulation may 30 be massive (india rubber, for example), applied in plastic condition; again, this insulation may consist fundamentally of a succession of solid bodies such as rings of porcelain strung upon the conductors; but most commonly the insulation for high voltage 35 cables is fundamentally composed of a body of fibrous material. This fibrous material is ordinarily paper or cloth in strip form wrapped spirally and in superposed layers 40 upon each conductor individually; and if there be a plurality of conductors within a single sheath, the individually wrapped conductors are assembled symmetrically about an axis, the spaces filled and the whole group- 45 ing built out to cylindrical form by coarser space-filling insulating substance (jute ordinarily or paper), and the whole cylindrical body is then ordinarily wrapped about with

another spiral wrapping, called the belt insulation, similar to that which encircles the individual conductors. A sheath of lead encloses and encloses the whole. Sometimes the fibrous strip or tape of paper or cloth is applied in its dry or natural condition; sometimes when applied it has already been 55 filled and coated with an insulating varnish; sometimes it may, before or at the time of wrapping, be filled or saturated with a substance called insulating compound, a substance ordinarily of oily or resinous nature, 60 effective to increase the dielectric strength of the insulation. The tape envelope may be wrapped on in dry state, and after wrapping on may be filled or coated with such an insulating compound; or, again, after the cable 65 has been otherwise so far completed as to be ready for the lead covering,—or, sometimes, at an earlier stage in the assembly, the entire 70 cable may be impregnated with such an insulating compound, by any of the several 75 methods known to the art.

In the accompanying drawings, Fig. I shows in cross section a cable of suitable character, to have our invention applied to it; Figs. II and III are similar views, illustrating modifications in structure.

Referring, first, to Fig. I, a typical three-conductor cable will be found illustrated. The individual conductors are indicated at 1; these are here shown to be solid conductors, but the showing is in this respect rather diagrammatic, and it will be understood that these conductors may be, and ordinarily they will be, stranded conductors, composed each of a bundle of relatively fine wires. However, in some cases, solid conductors will be used. About each conductor lies a wrapped-on envelope 2 of insulation. 3 is the central filler, ordinarily of jute; and 4 are the laterals, of the same material. The whole is 80 wrapped about with the belt insulation 5, and 6 is the lead sheath.

As has been explained, the bodies of insulation 2 and 5 are, ordinarily, built up of paper (or cloth) tape, wrapped on spirally 100 and in superposed layers. This wrapped-on material (we are speaking in generalizations, to include common variations in cable-making) may be cambric, varnished and dried before application; it may be cloth or paper, previously saturated with insulating

compound; or it may be dry or unfilled paper or cloth. Sometimes, though not necessarily, the wrapped-on material (particularly if previously saturated) is, at the time of wrapping, coated or flooded with insulating compound. The ordinary paper-insulated cable is made by wrapping the individual conductor 1 with the paper insulation 2 while the paper is still in dry or unfilled condition. The separately enveloped conductors are then assembled with the jute filling material 3, 4, and the belt insulation 5 is applied, in like manner as insulation 2. At one or more stages in this process the cable is dried, and its insulation is impregnated by immersion in insulating compound. The jute fillers 3 and 4 may or may not be preliminarily impregnated; but, ordinarily, in the building of paper insulated cables, these fillers are impregnated when (as usually occurs) the otherwise completed cable, ready for the lead sheath, is saturated by immersion in the compound.

In practicing our generic invention, a procedure may be adopted which, otherwise, would not commend itself; the whole body of insulation may be applied and built up, without any insulating compound whatever; the fibrous or porous material may be left quite dry. Indeed, it may in some cases be additionally preferable to omit the fillers 3 and 4. The specific invention of this application, however, involves impregnation.

In the application of massive insulation, such as india rubber, in the filling of fibrous or porous insulation with insulating compound, in filling with liquid or viscid substance the spaces between blocks of solid insulation,—in all of these cases it will inevitably be true that, however carefully the work be done, there will remain, not wholly dislodged by, but incorporated within the body of the insulation, bubbles (ordinarily minute) of air or other gas or water vapor. Such entrapped bubbles are points of weakness; their presence augments dielectric losses when the cable is in service, with consequent injurious heating of the cable; and, furthermore, their presence limits the voltage-carrying capacity of the cable; for by these bubbles as stepping stones disruptive electrostatic discharges of electricity make their way from conductor to sheath, unless the operating voltage of the cable be limited to so small a value that this effect cannot take place.

The point to which our explanatory statement now comes is that, in the insulation of all cables, bodies of air are present; ordinarily the bodies of air are unintended, undesired, and to the utmost degree possible (though never completely) eliminated. Our invention proceeds upon the acceptance of the presence of air (or other gas) as inevitable, and so deals with it that it shall

be relatively ineffective as a source of weakness. Indeed, it becomes itself in certain cases the effective dielectric. It follows that carefulness in the exclusion of air is not in the same degree necessary; and indeed, as we have just intimated, we may with advantage apply our invention to the air-filled or dry paper-insulated cable—a cable otherwise inadequate for ordinary high-power work. The air-filled cable is specifically claimed in the parent patent. The specific invention of this application concerns the cable whose insulation includes liquid or viscid substance.

Our invention consists fundamentally in putting the air present in the cable insulation (whether the quantity be reduced to the smallest possible unintended remnant, or whether it be the much greater intended quantity present in the dry or air-filled cable) under pressure, under a pressure of substantial amount. By substantial amount we mean a pressure so great that fluctuations due to changes of temperature under operative conditions (a range of 100° F., more or less) shall be relatively insignificant, in comparison with the actual value of the pressure. Practically, we find an absolute pressure of two atmospheres, (that is to say, one atmosphere above atmospheric) and upward adequate to effect the ends we have in view. Ordinarily the pressure used is much higher than two atmospheres, and ranges from 40 to 100 pounds to the square inch.

If it be a matter of small occluded bubbles of air or other gas, the substance in which the bubbles are held must, of course, at the time when the pressure is applied, be responsive to the pressure. If normally that substance be viscid or solid, it may for the purposes of our invention be rendered temporarily fluid—ordinarily by heat.

Pressure has two effects: in the case of occluded bubbles it reduces their size, and so is the equivalent of more complete elimination; but in all cases, that of the dry or air-filled cable as well, compression of the air or other gas decreases in marked degree dielectric leakage at high voltages and consequent heating, and increases in marked degree dielectric strength. In this breaking down of insulation the phenomenon of ionization of the pocketed air takes place, what is termed "internal corona effect" is brought about. The so segregated bodies of air are, under the stress of high voltage physically changed, so that they become electrically conductive.

Where a conductor carrying a high-voltage current is separated from another conductor body by an intervening air gap, the air is under a stress which increases as the voltage of the passing current increases. There is a critical point in this rise of voltage beyond which, if the point be exceeded, ionization of air in the gap will take place,

and electrical discharge across the gap will follow. The critical point in any such situation is a function of the pressure of the air in the gap. We have discovered, and here-
 5 in lies our invention, that the principle just stated may be applied with practical gain, in the building of high-tension cables. Hitherto all the effort has been to eradicate to the uttermost small pocketed bubbles of
 10 air; the impossibility of complete eradication has been a limiting circumstance, preventing more extended use of insulated cables. We have proceeded along a course widely variant from what hitherto has been
 15 universally held to be good and proper practice; we may cease to strive to the uttermost for the removal of air bubbles, or for the prevention of their occurrence; we may accept their presence as practically inevi-
 20 table; and we so deal with them as to render them innocuous and no longer sources of danger to the cable when in service. Indeed, we find that, as one application of our
 25 method, we can dispense with fluid insulating compound altogether; that we can build a dry cable, and make it effective. By pres-
 sure we so far raise the critical point of the contained air that within the intended ranges of voltage the critical point will not
 30 be reached, there will be no ionization of the air within the body of insulation, and no consequent breakdown, but the insulation will be good and effective.

While we may employ an air-filled fibre-
 35 insulated cable for the practice of our in-
 vention (specifically claimed in the parent
 case), it still will be borne in mind (as has
 already been explained) that the invention
 40 is applicable to a cable more or less com-
 pletely filled with insulating compound, to
 a cable insulated with massive insulation ap-
 plied in liquid or plastic form, and to a
 45 cable whose insulation consists fundamen-
 tally of blocks of solid insulation with filled
 or unfilled spaces between—it is applicable
 wherever the body of insulation contains
 50 air or other gas, whether in large and in-
 tended quantities, or in small, undesired,
 but ineradicable quantities.

If the insulation contains the air or gas
 55 in the form of occluded bubbles, and if the
 insulation be such in nature as to be sub-
 stantially solid under service conditions, it
 will be understood that the high pressure
 60 applied to the insulation while liquid, in
 order to bring about the essential condition
 of our invention, need not be continually
 maintained, after the insulation has solid-
 ified.

For special uses, where the exactions are
 65 exceptional, it will be advantageous to build
 up about the conductor an insulation which,
 in those parts nearest the conductor, where
 stress is greatest, is composed of such ma-
 terial as rubber or varnished cambric, and

in the outer and remoter parts consists of
 dry paper filled with air under pressure.
 The characteristic feature of insulation so
 built up will be that it consists of superposed
 70 layers, the underlying layers relatively mas-
 sive and the outer layers relatively open and
 filled with air under pressure. This ar-
 rangement will accomplish quite effectively
 75 the ends of "grading"—much more effec-
 tively, indeed, than can otherwise be accom-
 plished. Furthermore, the pneumatic pres-
 sure in the cable will be of additional ad-
 vantage in increasing the strength of the
 80 inner bodies of varnished cloth or rubber in
 the same way as the dielectric strength of a
 cable composed entirely of these materials
 would be increased by the use of the pneu-
 matic pressure. Such a graded cable has
 85 higher dielectric strength than a cable con-
 sisting wholly of either of the two kinds of
 insulation under consideration, and in par-
 ticular cases will be far more useful than
 either.

The structure just described is illustrated
 90 in Fig. III of the drawings which, in view
 of what has already been said, will be im-
 mediately and fully understood: 1 is the con-
 ductor, solid or stranded; 2^a is relatively
 massive insulation, such as rubber, or it may
 95 be varnished cloth; 2^b is relatively porous in-
 sulation, such as dry paper; and 6 is the
 cable sheath. The insulating layer 2^b will
 be understood to be filled with air (or other
 gas) and the gas to be maintained under
 100 pressure, as already described. The condi-
 tion of bubbles of air in the layer 2^a has been
 sufficiently dwelt upon.

Ordinarily in the practice of our inven-
 105 tion in one or another of its several forms,
 the pressure will be maintained in service
 by providing an air pump and an accumu-
 lator for compressed air (together with
 means for cleaning and drying the air).
 Communication will be maintained between
 110 the accumulator and the interior of the cable.
 Suitable check valves will be provided, to
 prevent accidental escape of air from the
 cable. Pressure may be distributed through-
 out the length of the cable by running a
 115 pressure supply pipe parallel with the cable
 (either within the cable sheath or outside)
 and providing ports of communication at
 suitable intervals.

When, as is herein specifically contem-
 120 plated, the insulation consists of or is filled
 with liquid, pressure may be maintained
 upon it, to compress occluded bubbles, in
 such manner as we have indicated, or the
 requisite pressure may be maintained by
 125 bringing a reservoir of liquid into communi-
 cation with the liquid insulation under a
 sufficient hydrostatic head.

Strength may be given to the cable sheath,
 as is well known, by alloying with the lead
 of which it is composed a very small amount
 130

of tin or other metal alloy. In common practice antimony, to an amount as great as 1%, or tin, up to about 3%, is used for this purpose. In some cases it will be found necessary or desirable to use a pressure much higher than can be withstood by a sheath of alloyed lead. In such case the sheath may be wrapped with steel or bronze tape. Such a wrapping is indicated at 17, Fig. III. 5

10 Since even a galvanized steel tape may be eaten gradually away by chemical or electrolytic action, it will in some cases be desirable to apply over such a wrapping of steel tape a second lead sheath. Again, the 15 lead sheath of the cable may be relieved of pressure from within tending to distend it, by placing the lead sheathed cable within an air-tight pipe or conduit and maintaining elevated pressure not only within the 20 sheathed cable but also in the space external to the cable and between it and the inner wall of the pipe. Such adaptation of material is of course to be made, wherever the user desires. 25

The primary advantage of our invention lies in the fact that the dielectric strength of the insulation will be considerably greater than that of cable insulation hitherto used. Thus it becomes apparent that it is possible 30 to operate a cable of given dimensions (of given amount of material and requiring a given amount of duct space) at a voltage fifty to one hundred per cent greater than is possible with the cables in use up to this 35 time. The importance of this advantage is far greater at extra high voltage than even at the voltage hitherto commonly used; for, if it were possible to remove from the cable hitherto used the limitation respecting 40 electric strength (that is to say, if the insulation would not break down under great strain and be disrupted and destroyed), still the dielectric losses of the kind already mentioned as leakage would become so great as 45 to forbid operation at voltages greatly exceeding the normal.

Over against the advantages stated must be set the expense (in most cases requisite) of maintaining the necessary pneumatic pressure. This is a disadvantage or inconvenience which is relatively greater in the case of short cable lengths than long; and it is relatively greater where the amounts of power carried are small than where they are 55 large. Furthermore, if the pressure required be so great as to approximate say 100 pounds per square inch, the cable (this has been intimated already) and the terminals may have to be specially constructed to withstand the pressure. 60

In the case of important cables, carrying large amounts of power over great distances, such special arrangements and construction of terminals as may be found requisite will be of little moment when compared with the

cost and importance of the cable itself. Again, since the practice of our invention permits transmission under voltages fifty to one hundred per cent greater than when a cable of the hitherto prevalent type is employed, two cables of our invention can do the work of three or four of equal size of the former type. Such a saving, manifestly, warrants increase of cost of cable and of terminals too, through a very wide margin. 70

Still another instance, where the advantages of our improved cable outweigh the disadvantages, is found in case a single-conductor cable (and, to limited extent, the same is true of a three-conductor cable) of 80 relatively short length connected to an open overhead line. Such a cable so connected may be of unusual importance, considering its length. In this case the advantages consequent on the use of our invention may 85 easily justify the added expense. If the short cable is to be used at a station in which terminate other cables of our invention, the economy of the use of the invention in the short cable will be still more clearly 90 apparent.

Where voltages are relatively low our invention will not, except under peculiar circumstances be advantageous. Peculiar circumstances, such as we have just suggested, 95 may, for instance, be found where temperatures are high and the possibilities for heat dissipation limited. But the principal field of usefulness of our invention is found with cables operating under load of 20,000 volts 100 and upwards. Without enlargement of dimensions, the voltage limit may, by the adoption of our invention, be increased from 20,000 to 35,000; from 25,000 to 40,000, or more. Or, if increase in voltage is not desired, thinner insulation may be used, with economy of space, or with advantageous enlargement of the conductor within. In either case, the cost per unit of transmitting power 105 would be less. 110

The possibility of increasing the operating voltage beyond the limit permissible for a cable of the type hitherto employed opens an entirely new field; it now becomes possible to transmit electric energy by cable 115 economically over much greater distances; for the distance economically possible is, within a wide range, proportionate to the voltage. For instance, where the distance is so great as to forbid the use of cables of types hitherto used, and to require instead the use of overhead transmission, it may now become good practice, by means of our invention, to resort instead to cable transmission. What has just been said was said 120 with multiple-conductor cables in mind; similar conditions obtain with respect to single-conductor cables, although the voltages permissible with single-conductor cables 125 would be possibly fifty to one hundred per 130

cent greater than with multiple-conductor cables. It is apparent, then, that a single-conductor cable embodying our present invention may be employed for carrying current under voltages heretofore possible for open-wire overhead transmission only. That is to say, in certain cases transmission by the single-conductor cable of our invention is possible, where previously cable transmission has not heretofore been possible by any means. 40

5

10

Sight must not be lost of the fact that when a cable of the present invention is applied in place of a cable of precedent type, even without any change in dimensions, and without change in voltage of operation, still the advantage will be enjoyed of diminished dielectric loss. 45

15

In the case of single conductor cables, designed for very high voltages, advantage will be found in the use of a hollow conductor; a conductor composed of a multiplicity of wires laid concentrically over the surface of a flexible conduit (made up or 50
